UNITED STATES PATENT OFFICE.

GUSTAVE BAEHR, OF PARIS, FRANCE.

COLLAPSIBLE HOOD OR ROOF OF VEHICLES.

Application filed March 31, 1921. Serial No. 457,467.

To all whom it may concern:

Be it known that I, GUSTAVE BAEHR, a citizen of the French Republic, and residing in Paris, France, 2, Rue des Sablons, mechanical manufacturer, have invented certain new and useful Improvements in and Relating to Collapsible Hoods or Roofs of Vehicles, of which the following is a complete specification.

10 Devices for mounting glazed frames intended for use in conjunction with motor cars provided with folding roofs are already known. These frames which are generally constituted by three parts hinged 15 connected so as to form the lateral surfaces of the motor car when the roof is unfolded, being located in the inoperative position, in a recess formed in the body of the car.

According to the described arrangement, 20 the whole of the glazed frame is simply introduced into the recess so that for putting the things in place it is necessary to raise the whole of these frames, this raising movement being effected by hand.

25 The present invention relates to a device for mounting glazed frames permitting of readily bringing them into either the inoperative or operative position without it being necessary to support manually the whole 30 weight of these frames.

In the accompanying drawing which illustrates a constructional form of the invention:

35 Figure 1 is a partial perspective view of the motor car showing the glazed frames arranged in the recess.

Figure 2 is a perspective view taken during the movement placing these frames in the operative position.

40 Figure 3 shows these frames in place before completely unfolding the device.

Figure 4 shows the glazed panel in the unfolded position.

45 Referring to Figure 1, the panels 22, 23, 24, are located in the inoperative position in the recess or chest 25, but in this constructional form, the central panel 23 is provided with hinges 40 pivoting about pins 41 provided on the lateral sides of the said recess or chest so that all the glazed panels 50 can pivot about these pins 41.

The external wall of the chest 25 is constituted by a panel 42 mounted through the

medium of the hinges 43 enabling the same to assume the position illustrated in Figure 2.

Should it be desired to convert the open carriage into a closed carriage, it is necessary, after having unfolded the roof, to open the panel 42, all the glazed parts are then swung about the pins 41 as shown in Figure 2, the whole thing is then swung upwardly, the central glazed panel 23 being hooked in a suitable manner to the frame of the folding roof, the glazed panels 22 and 24 being then unfolded in order to bring them over the corresponding parts of the body of the carriage.

In order to bring the whole arrangement into the inoperative position, the glazed panels 22 and 24 are closed upon the central glazed panel 23, all the three panels are then swung about the pins 41 and are brought into the recess 25 after opening the panel 42. The latter panel is closed and the carriage is thus converted into an open carriage.

This arrangement permits of rapidly and easily operating the glazed panels without it being necessary to lift the device bodily.

The hinges of the panel 42 may be vertical as shown in Figures 1, 2 and 4 or horizontal as shown in Figure 3; this panel may slide in or be otherwise secured to the body of the car.

What I claim is:

In a vehicle of the character described, a body having a recess in the outer face of its side, a hinged door for closing the recess, the door when closed being substantially flush with the outer face of the body, and three glazed frames hinged together to fold one upon the other, the middle frame being hinged at one end to the upper side edges of the said recess to swing upwardly and downwardly and the other frames hinged to the side edges of the middle frame to extend laterally therefrom and in alinement therewith or to fold on the same, whereby the frames when not in use and folded can be swung down into the recess and the recess closed.

In testimony whereof I have hereunto set my hand.

GUSTAVE BAEHR.
